UNITED STATES PATENT OFFICE.

ELBERT S. DODGE, OF ILION, NEW YORK, ASSIGNOR TO REMINGTON TYPEWRITER COMPANY, OF ILION, NEW YORK, A CORPORATION OF NEW YORK.

TYPEWRITING MACHINE.

1,411,238.

Specification of Letters Patent. Patented Mar. 28, 1922.

Application filed August 19, 1921. Serial No. 493,513.

To all whom it may concern:

Be it known that I, ELBERT S. DODGE, citizen of the United States, and resident of Ilion, in the county of Herkimer and 5 State of New York, have invented certain new and useful Improvements in Typewriting Machines, of which the following is a specification.

My present invention relates to carriage 10 feeding mechanism for typewriting machines, and its object generally stated is to provide new and improved means for feeding the traveling carriage step by step from left to right as is desirable in writing 15 Hebrew and similar languages.

A specific object of the invention is to adapt the Remington typewriting machine with very slight constructional changes to reverse the usual direction of feeding movement.

In the machine to which my invention is shown as applied, a carriage that supports a roller platen on which type bars act is drawn along step-by-step under the control 25 of an escapement, composed of a toothed wheel and feed dogs which coact with it. The carriages of these machines are thus drawn usually from right to left and in some instances from left to right, the direction 30 of the step-by-step travel depending on the language to be typewritten. The carriage of a machine embodying this invention is thus drawn from left to right. Such a machine may be used in writing the 35 Hebrew language and others, which are written in lines that are read from right to left.

The invention consists of features of construction, combinations and arrangements of 40 parts, which are set forth herein and defined in the claims.

In the accompanying drawings, which show only so much of a machine as it is believed to be necessary to illustrate in 45 setting forth a full, clear and exact description of the invention, and in which like reference numerals designate like parts in the different views.

Figure 1 is a side elevation and vertical 50 longitudinal section on the plane 1—1, Fig. 2, of a fragment of the machine, that fragment comprising the escapement mechanism and parts of the framework, carriage and carriage propelling mechanism;

55 Figure 2 is a plan of a fragment com-

prising parts of the escapement mechanism, framework, carriage and carriage propelling mechanism;

Figure 3 is a rear elevation and vertical cross section on the planes 3—3, Figure 2, 60 of a fragment comprising the escapement mechanism, carriage propelling mechanism, and parts of the carriage and framework; and

Figure 4 is a plan of a shaft-supporting 65 bracket.

All that is comprised in the machine and that is not illustrated herein, with the exception of the type, is contained in the well-known Remington typewriter which as illustrated herein, also comprises the top plate 5, platen carriage 7, fixed rail 8, rollers 10 and 11, rack bail 12, carriage rack 15, hanger 18, dog rocker 20, feed dogs 21 and 22, bracket 23, shaft 31, escapement 70 wheel 34, pawl 36, ratchet wheel 38, spring drum 44, strap 45, and link 46 engaging the pin 47 on dog rocker 20 at its lower end.

The rack bail 12 which includes the arm 13 at its left end and a similar arm at its 80 right end, is hinged to brackets fast on the carriage by the bolt 14 and another like it. The rack 15 is rigidly attached to the bail 12 by the screw 16 and another like it, which pass through the rack and into the 85 bail near its ends. The arrangement of this rack in the herein described machine is such that the vertical face of each of the teeth 17 is on the right of its sloping face instead of on the left as it is when the rack 90 is used in a machine that writes English. In other words, the right end of the rack in one machine is its left end in the other.

The hanger or stationary dog rocker support, at the top, extends across the recess 95 6 in the top plate 5 and is rigidly fastened to the top plate by screws driven into it from the upper side. The dog rocker 20 is pivotally mounted in the hanger so that it may rock on the pivot pin 19 and another pivot 100 pin secured in the hanger at the left side of the rocker. The bracket 23 stands on the hanger 18. The base 24 of the bracket, except close to the bottom, is in the recess 6 and it is fastened to the hanger by the 105 screws 29 and 30. The shaft 31 has at its front and rear ends respectively the journals 32 and 33, and the escapement wheel 34 is fixed to this shaft close to the journal 33, the set screw 35 passing through a hole 110

in the hub of the wheel and making contact with a seat on the shaft. The block 25, which is part of bracket 23, the front portion of which extends into the recess 9 in the fixed rail 8, forms the bearing of journal 32 and the tube 27 extending through part 26 of bracket 23, forms the bearing of journal 33. Part 26 is split and the screw 28 passes through the sections and when it 10 is tight the bearing tube 27 is clamped in the part 26 of the bracket. Pawl 36 is mounted on pin 37 fast in escapement wheel 34 and spring 39 supported by another pin fast in the escapement wheel forces the nose of the pawl against the teeth of the ratchet wheel 38. This ratchet wheel has internal teeth which act on pawl 36 and has external teeth besides. It is a duplex ratchet wheel and forms not only part of the means by 15 which motion is imparted to the escapement wheel from sleeve 40, but also a part of back spacing mechanism which Remington machines usually contain.

In the Remington English-writing machine, the ratchet wheel 38 constitutes an 25 enlargement of a rotary sleeve which surrounds and has bearings on the shaft of the escapement wheel and which the carriage turns, as it steps from right to left, so that 30 a tooth of the escapement wheel, on being released from the holding dog, moves to the right. The sleeve 40 in this machine is so turned, by force transmitted to it from the carriage as it steps from left to right. 35 Therefore the joint operation of the escapement wheel and feed dogs is the same in this machine as it is in the English-writing machines.

The strap 45, by which the spring drum 40 pulls the carriage along step-by-step and which in machines used in writing English is connected to an arm affixed to the carriage at its right end, passes from drum 44 to the under side of the roller 48 and thence 45 halfway around this roller and from the top thereof to the part 51 of an arm fast on the carriage at its left end. This arm includes the part 52 formed on and extending backward and upward from the base 53 50 which is fastened by screws 54 to the carriage. Part 51 is offset and extends downward from part 52 and has at its lower end a hook 55 and guard 56. Strap 45 is connected to hook 55 by the link 57 which is 55 attached to the strap and through which the hook passes. The roller 48, which has the flange 49, is loosely mounted on the screw stud 50 which is attached to the fixed rail 8. Hence, the spring drum, when it 60 imparts motion to the carriage, moves it from left to right.

The bracket or supporting arm 58, which is attached at its right end to bracket 23 by the screws 59 and which extends over 65 sleeve 40, has at its left end the block 60.

This is a bearing block in which the short shaft 61 is mounted and from which it projects at both the front and rear faces of the block. The shaft 61 is parallel to shaft 31 and the forwardly projecting part of shaft 70 61 extends underneath the rack 15. The gear 62 is fast on shaft 61 at its front end and normally is engaged by the rack. The gear 63 is fast on this shaft at its rear end and meshes with gear 43 on sleeve 40 behind the rack. It will be seen that the spring drum 44 acts through rack 15 on gear 62, and through gear 63 on gear 43, and through ratchet 38 and pawl 36 on the escapement wheel 34, and that as the carriage 80 steps from left to right wheel 34 turns in the same direction as does the escapement wheel of an English-writing machine when its carriage steps from right to left.

Whenever a printing key is actuated, link 85 46, connected to the universal bar of the machine pushes the lower end of the dog rocker backward. The carriage steps as the rocker returns to its normal position with the upward movement of the key.

The bracket or arm 58 and the bracket 23, fastened together by the screws 59, form a unitary support which is detachably secured to the hanger 18 and frame of the machine and on which is mounted operative 95 connections between the feed rack and feed dogs. This support with the mechanism mounted on it may be taken out of the machine on the removal of screws 29 and 30. The one piece bracket 58 with the shaft 61 100 and gears 62 and 63 mounted on it, may be removed separately when the screws 59 are taken out.

This invention enables the usual Remington English-writing machines quickly to be 105 changed so that a language which is read from right to left can be written with the machines. The bracket attached to the hanger of the dog rocker and the mechanism mounted on the bracket may be replaced 110 with the herein described bracket 23 and the mechanism shown mounted on it, this bracket including the arm 58, and the mechanism including the sleeve 40, gear 43, short shaft 61 and gears 62 and 63. The only 115 other changes needed and requiring the doing of mechanical work are the addition of the roll 48 and arm 51—52—53, the reversal of the rack and the equipment of the type bars with suitable type.

Although the invention is especially useful in Remington machines, it is not intended hereby to restrict it to use in such machines.

What I claim is new and desire to secure by Letters Patent, is:—

1. In escapement mechanism of typewriting machines, which comprises an escapement wheel, a shaft to which the wheel is affixed and which is supported at its ends by a fixed bracket, a rotary sleeve surrounding and 130

having bearings on said shaft, and means to impart motion from the sleeve to the wheel, only when the sleeve turns in one direction, the combination of a gear fast 5 on said sleeve, a short shaft parallel to said shaft and having a bearing in an arm of said bracket, a gear meshing with said gear and fast on the short shaft at one end thereof, and a gear with which the carriage rack 10 engages and which is fast on the short shaft at its other end.

2. In escapement mechanism of typewriting machines, which comprises an escapement wheel, a shaft to which the wheel 15 is affixed and which is supported at its ends by a fixed bracket, the front end of the shaft being below and in front of the carriage rack and the wheel being affixed to the shaft close to its rear end, a rotary 20 sleeve surrounding and having bearings on said shaft, the front end of the sleeve being close to the bearing at the front end of the shaft, and means to impart motion from the sleeve to the wheel only when the 25 sleeve turns in one direction, the combination of a gear fast on said sleeve behind the carriage rack, a short shaft parallel to said shaft and having a bearing in an arm of said bracket and extending forward 30 from said arm and underneath the carriage rack, a gear meshing with said gear and fast on the short shaft at the rear end thereof, and a gear fast on the short shaft at its front end and arranged to be engaged 35 by the carriage rack.

3. In a typewriting machine, the combination of a traveling carriage; a feed rack thereon; a dog rocker; feed dogs on said rocker; a unitary support detachably secured to the frame of the machine; and carriage feeding devices mounted on said support and providing operative connections between said feed rack and said feed dogs, said connections comprising a feed 45 pinion normally meshing with said rack, a toothed escapement wheel co-operative with said dogs, and constantly intermeshing gears connecting said pinion with said escapement wheel.

50 4. In a typewriting machine, the combination of a traveling carriage; a feed rack thereon; a dog rocker; feed dogs on said rocker; a unitary support detachably secured to the frame of the machine; and carriage feeding devices mounted on said support and providing operative connections 55 between said feed rack and said feed dogs,

said connections comprising a feed pinion normally meshing with said rack, a toothed escapement wheel co-operative with said dogs, and constantly intermeshing gears connecting said pinion with said escapement wheel, one of said gears being rigid with the shaft of the feed pinion and the other of said gears being mounted to turn rigidly 60 with the escapement wheel shaft during step by step letter feeding movements.

5. In a typewriting machine, the combination of a traveling carriage, a feed rack thereon, a dog rocker feed dogs on said 65 rocker, a toothed escapement wheel, an escapement wheel shaft, a gear wheel coaxial with said shaft, a detachable one-piece bracket, a feed pinion mounted on said bracket, and a second gear wheel also 70 mounted on said bracket and adapted to intermesh with the first recited gear wheel.

6. In a typewriting machine, the combination of a carriage, a spring drum constantly tending to turn to the left, a guide 75 roller, a band or strap connected to said drum and also to the left-hand end portion of the carriage, said band or strap running over said guide and tending to impel the carriage rightward, a feed rack on said carriage, a dog rocker, feed dogs on said rocker, a toothed escapement wheel, an escapement 80 wheel shaft, a gear wheel coaxial with said shaft, a detachable one-piece bracket, a feed 85 pinion mounted on said bracket, and a second gear wheel also mounted on said bracket 90 and adapted to intermesh with the first recited gear wheel.

7. In escapement mechanism of typewriting machines, in which mechanism an escapement wheel and shaft and means for transmitting motion thereto from the carriage rack are included, and in which means a short shaft and two gears are included, a supporting bracket on which the escapement 95 wheel shaft is mounted, and an arm which is attached to a part of the bracket and extends over the shaft of the wheel and on which said short shaft and two gears are mounted, the short shaft having a bearing 100 in the arm and the two gears being fast on the short shaft.

Signed at Ilion, in the county of Herkimer, and State of New York this 16th day of August, A. D. 1921.

ELBERT S. DODGE.
